HYDRAULIC MOTOR FOR DEEP-BORING
MECHANISMS

Theo Seifer, Berlin, Germany

Application November 26, 1935, Serial No. 51,633
In Germany February 27, 1935

9 Claims. (Cl. 255—4)

This invention relates to hydraulic motors for deep-boring mechanisms, more especially to such hydraulic motors in which a cylinder carrying the bit is vertically reciprocated by means of a flushing fluid the flow of which is controlled by means of a valve or valves.

The object of my invention is to release the valve or valves controlling the flow of the flushing liquid from the hydraulic pressure.

According to my invention I provide an auxiliary valve and a main valve controlled by the variation of the conditions of hydraulic pressure taking place when the auxiliary valve is opened or closed.

The main valve is according to my invention not only released from pressure but may also be protected against the concussions of moving water, because a small span of time intervenes between the closure of one valve and that of the other, the cylinder already rising in the meantime and being charged with water, (provided that the dimensions are correspondingly chosen).

Referring now to the drawings which are for illustrative purposes only,

Fig. 1 is a vertical cross-section through a part of the cylinder, the latter being in its highest position.

Fig. 2 shows the same parts as Fig. 1, with the cylinder in its lowest position.

Fig. 3 illustrates another modification.

Fig. 4 shows the valve according to Fig. 3, the cylinder assuming its lowest position.

Fig. 5 illustrates a complete boring mechanism including the chisel.

In Fig. 1, *a* is the hollow boring tubing through which the flushing and driving water is introduced into the cylinder. *b* is the cylinder of the hydraulic motor which is firmly connected with the chisel and in which the piston *d* may slide. The piston *d* is fixed to the tubing *a*. The piston divides the interior of the cylinder into two chambers. *e* are openings in the tubing *a* through which the flushing water enters the upper chamber of the cylinder. *f*₁ and *f*₂ are ducts through which the flushing water is transferred to the lower chamber of the cylinder *b*.

The tubing *a* is widened beneath the piston *d* to form a chamber in which the main valve *g*₂ and the secondary valve *g*₁ are arranged. The valve *g*₁ is firmly connected to the valve rod *h*₁ on which a collar *i* is provided. A cylinder *l* closed by a bottom *m* is concentrically connected with the cylinder *b*. In the bottom *m* ducts for leading the water to the chisel are provided. At its upper and lower end the cylinder *l* is equipped

with collar-like enlargements *n*. At the lower end of the tubing *a* levers *o*₁ and *o*₂ are fulcrumed cooperating with the rest *i* and sliding with rolls *q* on the outer surface of the cylinder *l*. *r*₁, *r*₂, *r*₃ are controlling springs of which *r*₁ rests on the control rod *h*₂. *s* is a bore in the valve *g*₂.

When the valves *g*₁ and *g*₂ are closed the water flows from the tubing *a* into the interior of the cylinder *b* above the piston *d* (position shown in Fig. 2). The cylinder is lifted together with the chisel (Fig. 5). It pushes upwards the rod *h*₂ which strikes upon the lower end of the rod *h*₁. On further raising the cylinder *b* the spring *r*₁ is more and more compressed, the levers *o*₁ resting on the upper side of the collar *i*. As soon as the lower enlargement *n* of the cylinder *l* reaches the rolls *q*, the latter are displaced aside and the collar *i* is released from the levers *o*₁. Now the compressed spring *r*₁ may open the valve *g*₁ so that the water is allowed to flow off from the chamber formed above the valve *g*₁.

The valve *g*₂ was hitherto pressed upwards against its seat, its lower surface being greater than its upper surface. The hydraulic pressure of the water was, during this period, assisted by the spring *r*₃. After the valve *g*₁ is opened a hydraulic pressure acts upon the upper surface of the valve *g*₂, the bore *s* letting less water flow off than the quantity of water flowing in through the tubing *a*. After opening the valve *g*₂ the flushing water flows off rapidly through the ports *f*₁ down to the chisel and the cylinder sinks down under the action of its own weight. The rolls *q* again roll off on the middle part of the cylinder *l*, the levers *o*₁ taking a position beneath the collar *i* and keeping the valve *g*₁ opened even when the compression of the spring *r*₁ ceases. This position of the levers and valves is illustrated in Fig. 1 in which the rests of the levers *o*₁ are shown lying under the collar *i*. The valve *g*₁ is closed only when the rolls *q* roll upon the upper enlargement of the cylinder *l* and the levers *o*₁ again release the collar *i* whereupon the hydraulic pressure again acts on the lower surface of the valve *g*₂ that is now likewise closed.

In Figs. 3 and 4 the surfaces of the valve chamber which are touched by the surfaces of the valves when closed are in another position than in the modification shown in Figs. 1 and 2.

In Figs. 3 and 4, *a* is the hollow tubing, *b* the cylinder sliding on the piston *d*. *e* is an opening in the tubing *a* through which the flushing water is introduced into the cylinder above the piston. *f*₁ and *f*₂ are openings through which the flush-

ing water flows from the interior of the tubing *a* beneath the piston *d* into the cylinder *b*.

g is the auxiliary valve and *g*₂ the main valve. *h*₁ and *h*₂ are the two parts of the valve rod. 5 Part *h*₁ is provided with a collar *i*. *l* is a cylinder connected with cylinder *b* and provided with enlargements *n*. *m* is a disk provided with ports for the flushing water through which cylinder *l* communicates with cylinder *b*. *o*₁ and 10 *o*₂ are levers fulcrumed at the lower end of the tubing *a* and cooperating with the collar *i*. The levers *o*₂ roll by rolls *q* upwards and downwards on the cylinder *l* when the cylinder *b* is raised or lowered. *r*₁, *r*₂, and *r*₃ are controlling springs.

15 In the modification shown in Figs. 3 and 4 the valve *g*₁ is closed by the valve rod *h*₁, *h*₂ and the spring *r*₁ when the cylinder has been raised. Now the valve *g*₂ is thrown upwards because the lower surface is greater than the upper one.

20 The flushing water now largely runs out and the cylinder drops down. Hereto the spring *r*₁ is released and in the corresponding relative position of the roll *q* and the cylinder the valve *g*₁ is pressed downwards and opened by the hydraulic pressure and under the action of the spring *r*₂ so that now the water pressure beneath the valve *g*₂ is reduced and the valve *g*₂ is closed, whereupon the cylinder is again raised.

25 By dividing the valve rod into two sections *h*₁ and *h*₂ it is possible to insert any desired free play between the lowest position of the cylinder and its position in the moment when the compression of the spring *r*₁ begins.

30 As shown in Fig. 4, the valve *g*₂ may be shaped to form a solid body, in which case the duct *s* may be formed by a cavity in the wall of the tubing connecting the space beneath the valve *g*₂ with the space above this valve. *r*₃ is a closing spring in Figs. 1 and 2 and an opening spring 35 in Fig. 3.

I claim:—

1. In a boring mechanism, the combination of a tubing through which the flushing fluid flows, a piston on the said tubing, a cylinder sliding over the piston, a main valve in the said tubing, a chamber in the tubing beneath the valve seat, apertures being provided in the said chamber for the discharge of the flushing fluid, an auxiliary valve in the said chamber, a rod extending from the body of the auxiliary valve and a second rod adapted to be lifted with the cylinder and adapted to strike the first named rod thereby opening the auxiliary valve after the cylinder has passed a certain way from its lowest position, the main valve being actuated by the variations of the hydraulic pressure connected with the opening and closing of the auxiliary valve.

2. In an impact boring mechanism actuated by flushing fluid the combination of a tubing, a piston mounted thereon, a cylinder slidably mounted on said piston, a boring tool carried by said cylinder and valve means for reversing the flow of fluid to said cylinder to cause reciprocation thereof, said valve means comprising a main valve and an auxiliary valve in said tubing, a chamber adapted to be closed by the main valve, a second chamber beneath the first one adapted to be closed by the auxiliary valve both chambers being 60 provided with outlet ducts, a rod extending from the body of the auxiliary valve and adapted to be lifted by the cylinder to open the auxiliary valve after the cylinder has passed a certain way from its lowest position, the main valve being controlled by the variation of the hydraulic pressure

in connection with the opening and closing of the auxiliary valve.

3. In an impact boring mechanism actuated by flushing fluid the combination of a tubing, a piston mounted thereon, a cylinder slidably mounted on said piston, a boring tool carried by said cylinder and valve means for reversing the flow of fluid to said cylinder to cause reciprocation thereof, said valve means comprising a main valve in the said tubing provided with an axial bore of a diameter smaller than the inner diameter of the tubing, an auxiliary valve in the tubing beneath the main valve, a chamber adapted to be closed by the main valve, a second chamber beneath the first one adapted to be closed by the auxiliary valve both chambers being provided with outlet ducts, the main valve being controlled by the variation of the hydraulic pressure in connection with the opening and closing of the auxiliary valve.

20 4. In an impact boring mechanism actuated by flushing fluid the combination of a tubing, a piston mounted thereon, a cylinder slidably mounted on said piston, a boring tool carried by said cylinder and valve means for reversing the flow of fluid to said cylinder to cause reciprocation thereof, said valve means comprising a main valve in the said tubing the body of which has a lower surface greater than its upper surface, an auxiliary valve in the tubing beneath the main valve, a chamber adapted to be closed by the main valve, a second chamber beneath the first one adapted to be closed by the auxiliary valve both chambers being provided with outlet ducts, the main valve being controlled by the variation of the hydraulic pressure in connection with the opening and closing of the auxiliary valve.

25 5. In an impact boring mechanism actuated by flushing fluid the combination of a tubing, a piston mounted thereon, a cylinder slidably mounted on said piston, a boring tool carried by said cylinder and valve means for reversing the flow of fluid to said cylinder to cause reciprocation thereof, said valve means comprising a main valve in the said tubing the body of which is provided with an axial bore of a diameter smaller than the inner diameter of the tubing and has a lower surface greater than its upper surface, an auxiliary valve in the tubing beneath the main valve, a chamber adapted to be closed by the main valve, a second chamber beneath the first one adapted to be closed by the auxiliary valve both chambers being provided with outlet ducts, the main valve being controlled by the variation of the hydraulic pressure in connection with the opening and closing of the auxiliary valve.

30 6. In an impact boring mechanism actuated by flushing fluid the combination of a tubing, a piston mounted thereon, a cylinder slidably mounted on said piston, a boring tool carried by said cylinder and valve means for reversing the flow of fluid to said cylinder to cause reciprocation thereof, said valve means comprising a main valve in the said tubing adapted to control the motor and provided with a spring actuating the said valve, and an auxiliary valve in the tubing beneath the main valve, a chamber adapted to be closed by the main valve, a second chamber beneath the first one adapted to be closed by the auxiliary valve both chambers being provided with outlet ducts, a rod extending from the body of the auxiliary valve and adapted to be lifted by the cylinder to open the auxiliary valve after the cylinder has passed a certain way from its lowest position, the main valve being controlled by the

variation of the hydraulic pressure in connection with the opening and closing of the auxiliary valve.

7. In an impact boring mechanism actuated by flushing fluid the combination of a tubing, a piston mounted thereon, a cylinder slidably mounted on said piston, a boring tool carried by said cylinder and valve means for reversing the flow of fluid to said cylinder to cause reciprocation thereof, said valve means comprising a main valve in the said tubing adapted to control the motor and provided with a spring adapted to open the said valve, and an auxiliary valve in the tubing beneath the main valve, a chamber adapted to be closed by the main valve, a second chamber beneath the first one adapted to be closed by the auxiliary valve both chambers being provided with outlet ducts, a rod extending from the body of the auxiliary valve and adapted to be lifted by the cylinder to open the auxiliary valve after the cylinder has passed a certain way from its lowest position, the main valve being controlled by the variation of the hydraulic pressure in connection with the opening and closing of the auxiliary valve.
- 10 8. In an impact boring mechanism actuated by flushing fluid the combination of a tubing, a piston mounted thereon, a cylinder slidably mounted on said piston, a boring tool carried by said cylinder and valve means for reversing the flow of fluid to said cylinder to cause reciprocation thereof, said valve means comprising a main valve in the said tubing adapted to control the motor and provided with a spring adapted to close the said valve, and an auxiliary valve in the tubing beneath the main valve, a chamber adapted to be closed by the auxiliary valve both chambers being provided with outlet ducts, a rod extending from the body of the auxiliary valve and adapted to be lifted by the cylinder to open the auxiliary valve after the cylinder has passed a certain way from its lowest position, the main valve being controlled by the variation of the hydraulic pressure in connection with the opening and closing of the auxiliary valve.
- 15 9. In an impact boring mechanism actuated by flushing fluid the combination of a tubing, a piston mounted thereon, a cylinder slidably mounted on said piston, a boring tool carried by said cylinder and valve means for reversing the flow of fluid to said cylinder to cause reciprocation thereof, said valve means comprising a main valve in the said tubing adapted to control the motor and provided with a spring adapted to open and to close the said valve, and an auxiliary valve in the tubing beneath the main valve, a chamber adapted to be closed by the main valve, a second chamber beneath the first one adapted to be closed by the auxiliary valve both chambers being provided with outlet ducts, a rod extending from the body of the auxiliary valve and adapted to be lifted by the cylinder to open the auxiliary valve after the cylinder has passed a certain way from its lowest position, the main valve being controlled by the variation of the hydraulic pressure in connection with the opening and closing of the auxiliary valve.

THEO SEIFER. 35
